UNITED STATES PATENT OFFICE.

KARL WESSEL, OF ST. PAUL, MINNESOTA.

BRIQUET-MACHINE.

No. 883,263.

Specification of Letters Patent. Patented March 31, 1908.

Application filed May 7, 1906. Serial No. 315,526.

To all whom it may concern:

Be it known that I, KARL WESSEL, a citizen of the United States, residing at St. Paul, in the county of Ramsey and State of Minnesota, have invented certain new and useful Improvements in Briquet-Machines; and I do hereby declare the following to be a full, clear, and exact description of the invention, such as will enable others skilled in the art to 10 which it appertains to make and use the same.

My invention has for its object to provide an improved briquet machine especially adapted for use to compress pulverized or 15 crushed peat and lignite into the form of solid blocks or bricks, usually designated as briquets.

To the above ends the invention consists of the novel devices and combinations of devices hereinafter described and defined in the 20 claims.

In the accompanying drawings which illustrate the improved machine, like characters indicate like parts throughout the several 25 views.

Referring to the drawings, Figure 1 shows the improved machine in side elevation. Fig. 2 is a front elevation of the same. Fig. 3 is a vertical section taken approximately on the 30 line $x^3 x^5$ of Fig. 2. Fig. 4 is a plan view of the head block of the mold, and Fig. 5 is a section taken on the line $x^5 x^5$ of Fig. 4.

The numeral 1 indicates a heavy bed casting which constitutes the frame of the machine, and is formed with three heavy upright bearing plates 2, and with an inclined front plate 3. In the upper portions of the bearing plates 2 is journaled a heavy transverse counter-shaft 4 which, as shown, carries a pair of eccentrics 5 and a pair of large 35 spur gears 6, one of which eccentrics is set 180 degrees ahead of the other, and which gears are spaced apart laterally and located outward of the outermost bearing plates 2. The gears 6 mesh with spur pinions 7 that are carried by the driving shaft 8, that is mounted in suitable bearings on the upper rear portions of the bearing plates 2. As shown, this driving shaft 8 carries a pair of fly-wheels 9 and a driving pulley 10, over the latter of 50 which a power-driven belt (not shown) will in practice be run to impart motion to the said driving shaft 8.

On the lower portion of the inclined front bearing plate 3 of the machine frame is a heavy bearing lug 11, the outer portion of

which, as shown, is rigidly tied to the upper portions of the upright bearing plates 2, by means of heavy tension bolts or rods 12. On the bearing lug 11 is rigidly seated a 30 heavy bushing 13, the upper end of which is flanged to limit its downward movement in its seat within the lug 11. This bushing 13 is set with its axis inclined and parallel to the inclined face of the bearing plate 3 and also 35 parallel to the tie bolts or rods 12. Firmly seated within the bushing 13 is a sleeve-like mold or die 14 having, as shown and preferred, a longitudinally-extended bore or plunger seat that is round in cross section. 40 About one-half of the lower portion of the mold 14 is cut away throughout approximately 180 degrees, and the seat thus formed is fitted with a segmental supplementary sleeve section 14^a. The sleeve-like mold 14 45 is preferably flanged at its upper end, and has threaded engagement with the upper end of the bushing 13, so that it is firmly held therein and cannot be forced axially downward into the bushing 13 farther than shown 50 in Fig. 3. The supplementary sleeve section 14^a is also formed with a flange 14^b at its upper end that engages a seat formed therefor in the bushing 13, and locks the said supplemental section against endwise movement, and at the same time affords a fulcrum 55 permitting the lower portion of said supplemental section to move laterally to a slight extent with respect to the lower end of the notched portion of the sleeve-like mold 14. 60 The longitudinal edges of the supplemental mold section 14^a are slightly tapered so as to permit a slight oscillatory or angular movement with respect to the lower end of the mold, this being done for an important 65 purpose which will hereinafter appear. The said supplemental mold section 14^a is adapted 70 to be adjusted by a set-screw 15 that works through the lower end of the bushing 13 and impinges against the outer surface thereof, as best shown in Fig. 3. The numeral 75 16 indicates a cap-nut which is adapted to be screwed onto the lower end of the mold,—the lower end of the notched portion of said mold and the lower end of the supplemental 80 section 14^a being threaded to receive this cap-nut. The purpose of this cap-nut will 85 also be presently stated.

Rigidly secured to the inclined front bearing plate 3 of the machine frame is a plunger-guiding block 17. A compression plunger 18 works in the seat of the block 17 and

moves into and out of the mold 14. The seat for the plunger 18 in the block 17 is formed with a lateral opening 19 that receives direct from the lower end of a supply hopper 20, that is rigidly secured to the machine frame and to the said block 17. The compression plunger 18 is rigidly secured to a cross-head 21 mounted to reciprocate on a cross-head guide 22, that is rigidly secured 10 to the inclined bearing plate 3, and extends in a plane parallel to the plane of the axis of the mold 14 and plunger 18.

The mold, compression plunger, cross-head and supply hopper above described are in the preferred form of this machine arranged 15 in duplicate, and each of the two cross-heads 21 is connected to one of the two eccentrics 5 above described, by a heavy eccentric strap and connecting rod 23. By this arrangement one of the compression plungers 18 will be given its operative or down stroke while the other is being given its inoperative or upward stroke. Otherwise stated, the two compression plungers will be thrown 20 into action in alternate order.

The pulverized or crushed lignite, peat, or solid material which is to be compressed into briquet form is placed in the hopper 20 and will be supplied to the molds through 25 the ports or slots 19 of the guide blocks 17. When the plungers 18 are in their extreme uppermost positions their lower ends will be carried above the said ports 19, so that the pulverized material may then run into the 30 plunger seat of the block 17 and into the bore of the mold. When the compression plunger is moved downward and into the mold it compresses the material in the mold into 35 briquet form. The several blocks or bricks will always remain within the mold, and to force these out of the mold in succession as the successive briquets are 40 compressed requires a very considerable force. The amount of force required, and hence the 45 frictional resistance, may be varied at will by angular adjustments of the mold section 14^a. When the said mold section 14^a is adjusted with its cylindrical surface parallel to the cylindrical surface of the body of the 50 mold, no very great friction will be put upon the formed blocks. But when the lower end of said mold section 14^a is forced laterally inward so as to contract the lower end of the mold, very great friction may be put 55 upon the formed blocks so that a very great compressing force of the plunger 18 on the block being compressed will be required to effect the discharge of the lowermost of the briquets from the mold. Hence, by the 60 adjustments of the said mold section 14^a the base of reaction which the briquets within the mold offer to the compressing force may be so varied that any desired compression 65 may be put upon the briquets.

For the purpose of effecting a proper com-

pression of the first few briquets formed in the mold, the cap-nut 16 should be applied to the lower end of the mold, as indicated by dotted lines in Fig. 3. After the said first few blocks have been compressed within the 70 mold, the said cap-nut must be removed, and the mold section 14^a must then be properly adjusted. When the briquets are compressed in rapid succession a great deal of heat is generated so that the mold will get 75 hot. A considerable amount of heat is desired in the mold in order to properly fuse or melt together the outer particles of the briquet-forming material, and thereby insure 80 briquets of solidified form and which are capable of considerable rough handling without breaking. In cases where too great heat is produced the mold may be water-jacketed, and for this purpose (see Fig. 3) the bushing 13 is shown as formed with angular chambers 13^a that directly surround the mold. The water-circulating connections to and from the water chambers 13^a are not shown in the drawings, and it is not necessary for the purposes of this case to further consider 85 the same.

By the arrangement above described, whereby the two compressing plungers are thrown into action in succession instead of being thrown into action simultaneously, a 90 great economy and power are accomplished and a much lighter machine is made possible. It is, of course, evident that the machine arranged to compress the briquets in succession as above described, may be no heavier 95 or stronger than a machine of the same character having but one briquet-forming die and compression plunger, since the work of compressing the two briquets comes at different times, and the maximum strain on 100 the machine is measured by the force required to compress one briquet.

The compression plungers 22 always maintain engagement with the guide-block 17, but when moved to their extreme uppermost 105 positions are raised high enough to entirely open up the inlet ports 19. It will, of course, be understood that three, or even four, molds in the compression plungers may be employed and that all may be operated by 110 a common power transmission mechanism arranged to throw said plungers into action in succession, and in such manner that only the material of the dies will be subjected to 115 high compression at any one time.

I claim as my invention:

1. In a machine of the kind described, the combination with a mold and a coöperating compression plunger, of means for reciprocating said plunger, and a cap rigidly but 120 detachably securable to the delivery end of said mold and serving when applied to confine the material being compressed within the mold, substantially as described.

2. In a machine of the kind described, the 125

combination with a mold and a coöperating compression plunger, said mold having at its delivery portion a segmental section, means for imparting a lateral angular adjustment to said segmental mold section to contract the delivery end thereof, means for reciprocating said plunger, and a cap rigidly but detachably securable to the delivery end

of said mold, substantially as described and for the purposes set forth. 10

In testimony whereof I affix my signature in presence of two witnesses.

KARL WESSEL.
